DESIGN FOR A PANEL MAT

William J. Adams, Jr., Hartsdale, N. Y., and William A. Woods, East Orange, N. J., assignors to Bell Telephone Laboratories, Incorporated, New York, N. Y., a corporation of New York

Application December 28, 1934, Serial No. 54,630

Term of patent 14 years

To all whom it may concern:

Be it known that we, William J. Adams, Jr., and William A. Woods, citizens of the United States of America, residing at Hartsdale, in the county of Westchester and State of New York, and at East Orange, in the county of Essex and State of New Jersey, respectively, have invented a new, original, and ornamental Design for a Panel Mat, of which the following is a specification, reference being had to the accompanying drawing, forming a part thereof.

Fig. 1 is a front face plan view of the panel mat and showing our new design; and

Fig. 2 is a view in cross-section of the panel mat taken on the line 2—2 in Fig. 1 and viewed in the direction indicated by the arrows.

Figs. 1 and 2 are drawn to the same scale.

We claim:

The ornamental design for a panel mat, as shown.

In witness whereof, we hereunto subscribe our names this 26th day of December, 1934.

WILLIAM J. ADAMS, JR.
WILLIAM A. WOODS.
